UNITED STATES PATENT OFFICE

150,952

DESIGN FOR A RING OR SIMILAR ARTICLE

Anton Hoecke, Providence, R. I., assignor to Clark & Coombs Company, a corporation of Rhode Island

Application August 23, 1947, Serial No. 141,023

Term of patent 7 years

(Cl. D45—10)

To all whom it may concern:

Be it known that I, Anton Hoecke, a citizen of the United States of America, residing at Providence, county of Providence, State of Rhode Island, have invented a new, original, and ornamental Design for a Ring or Similar Article, of which the following is a specification, reference being had to the accompanying drawing, forming a part thereof.

Fig. 1 is a top plan view showing my new design for a ring or similar article;

Fig. 2 is a side elevational view; and

Fig. 3 is an edge view.

The dominant part of the design is shown in full lines.

I claim:

The ornamental design for a ring or similar article, substantially as shown and described.

ANTON HOECKELE.
